UNITED STATES PATENT OFFICE.

ALEXANDER LAWRENCE CURRIE, OF SOREL, QUEBEC, CANADA.

PORTABLE RAILWAY-SIGNAL.

1,301,914.

Specification of Letters Patent. Patented Apr. 29, 1919.

Application filed September 21, 1918. Serial No. 255,122.

To all whom it may concern:

Be it known that I, ALEXANDER LAWRENCE CURRIE, a subject of the King of Great Britain, and resident of the village of Sorel, in the Province of Quebec, Dominion of Canada, have invented certain new and useful Improvements in Portable Railway-Signals, of which the following is a specification.

This invention relates to improvements in portable railway signals of that type adapted to be utilized by section gangs when working on and repairing a railway track, and the objects of the invention are to facilitate positioning the flag with such a degree of security, that there is no possibility of the flag becoming displaced, due either to wind, rain or snow storms, or jarring, or vibration of the track, or to any other causes met with in railway practice, to provide means whereby the flag carried by the signal can be readily adjusted, and to render the signal collapsible and permit of it being folded into a compact bundle for carrying.

Further objects are to permit of a fabric or like flag being used, one portion of which will always be maintained with its face exposed to the view of the engineer of an approaching train, while at the same time lateral wings are provided which will flutter in the breeze and assist in attracting the engineer's attention, to simplify the construction of the signal, and render the same fool proof.

With the above and other objects in view the invention consists essentially of the improved construction particularly described and set forth in the following specification and accompanying drawings forming part of the same.

40. In the drawings:

Figure 1 is a front elevation on one form of the invention.

Fig. 2 is a fragmentary front elevation of the improved signal showing an alternative means of positioning the same.

Fig. 3 is a fragmentary front elevation of the signal showing another method of securing the same in position.

Fig. 4 is a fragmentary perspective view of the rail showing a wedge means illustrated in Fig. 3 for securing the signal to the lower flange of a rail.

Fig. 5 is a perspective view of a signal

showing an alternative means of securing the same to a fish plate.

55

Fig. 6 is a plan view of the locking plate designed to secure the rod and tubular member of the signal in operative position.

Fig. 7 is a front elevation of the frame of the flag on which the fabric flag is designed to be mounted.

Fig. 8 is a front elevation of the fabric flag.

Fig. 9 is a side elevation of the metallic flag shown in Fig. 1.

65

Fig. 10 is a side view of an alternative form of the invention.

Fig. 11 is a plan view of the form shown in Fig. 1.

Fig. 12 is a sectional view of an alternative form of the invention.

Like characters of reference refer to like parts in the several figures.

Referring to the drawings, A represents the improved signal which comprises a rod 75 10 pivotally secured to the upwardly extending offset arm or portion of the tube 11 which arm is split open to permit of the rod 10 being rotated about its pivotal point and lie along the longer portion or arm of the tubular member when the flag is being carried from place to place.

80

The tubular member 11 has the upper end of its shorter arm cut away as shown at 12 and a locking plate or washer 13 is provided which slidably engages with the rod 10 and cut away portion 12 to secure the said rod and tubular member 11 in open serviceable position.

85

The locking plate 13 may be secured to the tubular rod by a chain 14 or other like member.

The upper end 15 of the rod 10 is flattened and offset and in the embodiment illustrated in Figs. 1 and 8 a metallic flag 16 is provided which is formed with U-shaped brackets 17 on the back thereof designed to slidably engage with the offset end 15 and so secure the flag in position.

95

This flag may be provided with orifices 100 18 on opposite sides when such is found necessary and convenient in railroad practice.

The longer arm of the tubular member 11 carries a rod 19 which is secured in position 105 by rivets or the like, and this rod is pro-

vided with orifices through which screws 20 pass to secure the signal A to the tie B of the railway bed.

In Fig. 2 a modification of the rod 19^a 5 is shown, and in this case the rod is provided with a bifurcated end 21, which embraces one portion of the lower flange of a rail and a set screw 22 is threaded through one arm of the bifurcated end to frictionally 10 engage with the lower flange of the rail and so secure the signal A in position.

In Fig. 3 another form of rod 19^b is provided in which the ends terminate in a pair of jaws 23 adapted to embrace the lower 15 flange of a rail, and a key 24 is driven between one jaw and the said flange to frictionally hold the signal A in position.

This key 24 is secured to the rod 19^b by a chain or like member 25, so that the key 20 will not become lost or displaced.

In Fig. 5 the rod 19^c is provided with an offset end 26 which is designed to abut and lie along the upper face of the lower flange of a rail and at one side thereof, and 25 then to abut or engage with the web of the rail, the end of the rod then being bent to be inserted between the web of the rail and fish plate 27, in which position it is retained by a set screw 28 passing through the said 30 fish plate.

Under some circumstances it may be found advisable to use a fabric flag instead of a metallic plate, and to this end I provide a skeleton frame 29 of substantially U-shape provided with a transverse arm 30 intermediate of the height of the side arms, and this arm and the lower transverse member of the frame are provided with orifices through 35 which the upper offset flattened end 15 of the rod 10 passes.

The upper ends of the side arms of the U-shaped frame 29 are bent inwardly as shown at 31, and these side arms are adapted to engage with hems 32 on the side of the 45 fabric flag 33, so that the body of the flag 33 will be held with the face exposed to the engineer of an approaching train.

To prevent any tendency to displacement of the flag 33 an eyelet 34 is provided which 50 engages with the flattened end 15 of the rod 10 and is located between the lower transverse arm of the U-shaped frame 29 and the transverse arm 30.

In this position it will be seen that the 55 flag 33 cannot work loose and can only be removed from the frame after the said frame has been removed or disengaged from the rod 10.

The flag 33 is provided with lateral wings 60 35 which will trail or flutter in the wind, and so tend to provide an extra attraction to the engineer of an approaching train.

When the signal is in use it is attached to the tie B of the rail bed as shown in Fig. 1, 65 or to the lower flange of the rail as shown

in Figs. 2 to 5, whereupon the rod 10 is rotated about its pivotal point until it assumes the position as shown in Fig. 1 in which it is locked by the plate 13.

The metallic flag 16 may then be positioned on the rod 10 and the signal is in condition for use.

If the fabric flag is being used, it is positioned on the frame 29 with the side arms of the said frame engaged with the hem 32 75 on the edge of the flag, and the eyelet 34 engages with the flattened end 15 of the rod 10 and is located between the lower transverse arm and the arm 30 of the frame 39, the flag is now in condition for use. 80

At night time a lamp will be used in conjunction with the flag 16 or 33, and will be hung by any convenient means. For instance when the flag 33 is used, the lamp may be hung or suspended from the flattened 85 end 15 of the rod 10.

In the alternative form shown in Figs. 10 and 11 a fabric flag 40 is supported on cross bars 41 and 42 which are mounted on a flattened end 15 of the rod 10, the cross bars 90 41 and 42 extend along top and bottom respectively of the flag.

In the form of the invention shown in Fig. 12 a torpedo 50 is provided adjusted to the track adapted to be exploded by a 95 plunger 51 engaged by a wheel 52 of the locomotive or car.

The plunger operates in a cylinder 53 and strikes the torpedo therein. Where an automatic train stop device is to be used, a 100 ramp or bracket 60 may be provided as shown in Fig. 1, bolted to the member 19.

As many changes could be made in the above construction and many apparently widely different embodiments of my invention within the scope of the claims constructed without departing from the spirit or scope thereof, it is intended that all matter contained in the accompanying specification and drawing shall be interpreted as illustrative and not in a limiting sense. 110

What I claim as my invention is:

1. A portable signal comprising a tubular rod offset intermediate of its length, a rod rotatably mounted on the shorter arm of 115 the tubular rod, a rod rigidly attached to the longer arm of the tubular rod, attaching means connected to the last said rod, a flag carried by the first said rod, and lateral wings on the flag. 120

2. A portable signal comprising an offset tubular rod, a rod rotatably attached to the tubular rod having its upper end offset, a movable flag on the offset end of the rod, a rod rigidly attached to the tubular rod and terminating in jaws adapted to embrace the lower flange of the rail, and key means engaging with the said flange and one of the jaws. 125

3. In a portable signal a skeleton frame of 130

substantially U-shape, a transversely extending member connecting the side arms intermediate of the height thereof, a flag engaging with the arm, and lateral wings on the 5 flag.

4. In a portable signal a U-shaped frame having side arms terminating in inwardly offset ends, a fabric flag having hems on the side edges adapted to engage with the side 10 members of the frame, and wings on the flag.

5. A railway signal of the class described comprising a base member, said base member including a tubular member offset intermediate of its length and having its upper arm open toward the inner side, and a flag carrying member rotatably mounted in the 15 open end of the tubular member.

6. A railway signal of the class described comprising a base having suitable attaching means, a tubular member co-acting with the base and offset intermediate of its length, the upper end of the tubular member being 20 offset and reduced toward the upper end to form a shoulder, a flag carrying member rotatably mounted to the open upper arm of the tubular member, a ring slidably mounted on the flag carrying member adapted to co-act with the shoulder and secure the 25 flag carrying member in upward angular position.

7. A railway signal of the class described, comprising a base, a tubular member co-acting with the base offset intermediate of 30 its length and having its upper arm open

toward the inner side, a flag carrying member rotatably mounted to the open upper arm of the tubular member, a tongue on the tubular member, a ring slidably mounted on the flag carrying member adapted to be 40 slid over the tongue and below the same and rotated to lock the flag carrying member in an upright angular position.

8. A railway signal of the class described comprising a base, a flag carrying member 45 rotatably connected to the base and a wire frame of substantially U-shape having its parallel arms terminating in ball ends and provided with an offset portion intermediate of its transverse arm adapted to be secured to the flag carrying member, as and for the purpose specified. 50

9. A railway signal having a flag supporting member a pair of bars mounted on the supporting member in parallel relation and 55 a flag engaged by the said bars, and provided with side wings as and for the purpose specified.

10. In a portable signal, an arm, a signal on the arm, and means for attaching the arm 60 to the rail comprising a member adapted to be inserted between the web of the rail and the angle iron, and means for retaining such member in position.

In witness whereof I have hereunto set my 65 hand in the presence of two witnesses.

ALEXANDER LAWRENCE CURRIE.
